UNITED STATES PATENT OFFICE

JOHN J. FOX, OF SAGINAW, MICHIGAN

ILLUMINATED SIGN

Application filed June 9, 1927. Serial No. 197,612.

This invention relates to signs of that type embodying a transparent glass plate having the character or characters thereof formed or outlined by light reflecting portions, and a lamp arranged to cast its rays edgewise through the glass plate so as to illuminate such portions. Signs of this character have not met with general approval for the reason that the light reflecting portions thereof, which are formed by cutting the required parts of the rear side of the glass plate by the sandblast process, have when illuminated a dull, shady or frosty appearance and do not therefore render the character or characters clearly visible.

The present invention has for one of its objects to improve signs of this character by providing them with light reflecting portions which when illuminated will have a bright, shiny appearance and which will due thereto render the character or characters clearly visible, the invention comprehending the provision of the light reflecting portions by cutting the required parts of the rear side of the glass plate with a steel punch.

A further object of the present invention is to provide a novel frame and support for the glass plate and to provide the glass plate with an opaque backing which will also assist in rendering the light reflecting portions bright and shiny in appearance.

With the foregoing and other objects in view, the nature of which will become apparent as the description proceeds, the invention consists of the construction, combination and arrangement of parts hereinafter fully described and claimed, and illustrated in the accompanying drawings, wherein:

Figure 1 is a view in front elevation of a sign constructed in accordance with my invention,

Figure 2 is a sectional view taken on the horizontal plane indicated by the line 2—2 of Figure 1,

Figure 3 is a sectional view taken on the vertical plane indicated by the line 3—3 of Figure 1,

Figure 4 is an elevational view illustrating a slightly modified form of the glass plate of the sign, and

Figure 5 is a similar view of a further modified form of the glass plate of the sign.

Referring in detail to the drawings, 1 designates the glass plate of the sign. This part is transparent, and the character thereof may be a figure as shown in Figure 1 or a word or words as shown in Figures 4 and 5. If desired, the glass plate 1 may be provided with characters in the form of figures and words. The character or characters may be formed as shown in Figures 1 and 5 or outlined as shown in Figure 4 by light reflecting portions 2 which are provided by indenting or cutting the rear side of the glass plate by means of a steel punch. The light reflecting portions 2 are, due to the manner in which they are provided, of such character that when illuminated they have a bright, shiny appearance and render the character or characters of the sign clearly visible.

The glass plate 1 is secured in a frame 3 which is open at its front and closed at its back and at its top and side edges, and a black felt pad is positioned between the glass plate 1 and the back of the frame 3. The side and top edges of the glass plate 1 have a tight fit with the sides and top of the frame 3 so as to prevent light rays from passing into the glass plate by way of these edges. The frame 3 is supported by a hollow base 5 which constitutes a lamp compartment and into which the lower edge of the glass plate 1 extends. The base 5 is provided in its upper side with a slot 6 for the reception of the lower end portion of the glass plate 1, and it is provided on the interior thereof with strips 7 which constitute rests or supports for the glass plate. A pin 8 carried by the top of the frame 3 contacts with the glass plate 1 and securely holds it in place.

A lamp 9 of the incandescent electric type, is arranged within the base 5 so as to cast its rays edgewise through the glass plate 1. The lamp 9 may be colored or plain, and the rays emanating therefrom enter the lower edge of the glass plate 1 and pass upwardly throughout the entire area thereof and illuminate the reflecting portions 2. The lamp 9 is carried by a socket 10 which is secured to a door 11 located at the rear side of the base 5. Leads 100

12 are connected to the socket 10 to permit the lamp to be supplied with current from an electric light socket or from any other suitable source.

As reflecting portions 2 of the glass plate 1 are formed by cutting the required parts of the rear side of the glass plate by means of a steel punch, these portions will be clearly and brilliantly illuminated by the passage of the 10 light rays through the glass plate. Due to the brilliant illumination of the reflecting portions 2 and to the opaque backing 4 of the glass plate 1, the character of the sign formed solidly or outlined by the reflecting 15 portions will be clearly visible. The base 5 adapts the sign to be supported on a counter, showcase or the like.

It should be understood that the drawings are merely illustrative and do not pretend 20 to give exact proportions. Furthermore, the said drawings are illustrative of a preferred construction, it being my expectation that various changes and modifications may be made without departing from the spirit and scope 25 of my invention.

What is claimed is:—

A sign of the character set forth comprising a hollow base provided on its upper side with opaque walls having a slot therebetween, 30 strips secured within the base at opposite sides thereof and extending across the slot, a frame extending upwardly from the base and fitted in the slot and closed at its rear side, a glass plate disposed within the frame having its 35 lower edge portion positioned in said slot and resting upon the strips, the location of said strips affording a construction wherein said lower edge portion of the glass plate is unobstructed between the strips, and a lamp with- 40 in the base.

In testimony whereof I affix my signature.
JOHN J. FOX.
